(57) **CLAIM**

The ornamental design for a lifting device, as shown and described.

DESCRIPTION

FIG. 1.1 is a front, plan view of a first embodiment of a lifting device, according to my new design;

FIG. 1.2 is a top plan view thereof;

FIG. 1.3 is a right, plan view thereof;

FIG. 1.4 is a top, right perspective view thereof;

FIG. 1.5 is a bottom, left perspective view thereof;

FIG. 1.6 is a top, left perspective view thereof; and

FIG. 1.7 is a left, plan view thereof.

FIG. 2.1 is a front, plan view of a second embodiment of a lifting device, according to my new design;

FIG. 2.2 is a top, right perspective view thereof;

FIG. 2.3 is a bottom, left perspective view thereof;

FIG. 2.4 is a top, left perspective view thereof;

FIG. 2.5 is a right, plan view thereof;

FIG. 2.6 is a left, plan view thereof; and

FIG. 2.7 is a top plan view thereof;

The broken lines shown in the drawings depict portions of the lifting device that form no part of the claimed design.
